(No Model.)

F. LANSBERG.

GOVERNOR FOR FLUID COMPRESSORS OR PUMPS.

No. 415,519.

Patented Nov. 19, 1889.

UNITED STATES PATENT OFFICE.

FRANK LANSBERG, OF ST. LOUIS, MISSOURI, ASSIGNOR TO THE LANSBERG BRAKE COMPANY, OF EAST ST. LOUIS, ILLINOIS.

GOVERNOR FOR FLUID COMPRESSORS OR PUMPS.

SPECIFICATION forming part of Letters Patent No. 415,519, dated November 19, 1889.

Application filed April 29, 1889. Serial No. 308,937. (No model.)

To all whom it may concern:

Be it known that I, FRANK LANSBERG, of the city of St. Louis, in the State of Missouri, have invented a certain new and useful Improvement 5 in Governors for Fluid Compressors or Pumps, of which the following is a full, clear, and exact description, reference being had to the accompanying drawing, forming part of this specification, and which is a vertical section. 10

My invention relates to the construction of a valve for air-brakes wherein the supply of steam to work the air-pump is automatically cut off when the air has reached a certain 15 pressure.

Referring to the drawing, 1 represents the inlet-pipe of the cut-off (or the pipe from the boiler) and 2 the outlet, (or the pipe to the pump.)

20 3 represents the valve through which the steam passes.

4 represents the air-inlet of the cut-off with which the train - pipe, or the pipe from the pump, operated by means of the steam passing through the ports 1 and 2, communicates.

Within the housing 5 is a valve 6, with downwardly-extending wings 7, which is secured to an upwardly-projecting valve-stem 6^a, which latter projects loosely through a 25 valve 8, having a small port 9, and terminates at its upper end under a valve 3, opening downwardly and adapted to be closed by the opening of the valve 6. Secured to or made integral with the valves 3 and 8 is a neck or 30 sleeve 16, and located within this sleeve, under the valve 3 and surrounding the valve-stem and passing through the valve 8 and resting upon the valve 6, is a spring 19, adapted to hold the valve 3 to its seat and the valve 8 off 35 of its seat against their own gravity. Located below the valve-wings 7, in a chamber 14, is a piston 10, having an upwardly-extending neck 11 and guide-wings 12.

40 13 represents a blow-off or escape valve. 45 The operation is as follows: The steam passes through the port 1, opens the valve 3, passes out through the port 2, and is conveyed to and operates the pump. When the air has reached a certain pressure in the pipe 50 which connects with the port 4, it raises the piston 10 by entering the chamber 14 beneath

the piston. This causes the neck 11 to abut against the wings 7 and raise the valve 6 from its seat, which action allows free passage of the steam down through the port 9, whence it 55 escapes past the valve 6 via the passage 17, and leaves the housing through the exhaust-cock 13, thus relieving a portion of the pressure above the valve 8 and rendering the latter more easily lifted. As the valve 6 moves 60 upward, it comes in contact with the valve 8 and raises the latter from its seat, while by the same pressure the valve 3 is closed and the source of steam cut off from the port 2, and the steam remaining in the latter allowed free 65 escape past the valve 8. As soon as the pressure in the pipe 4 diminishes until it is less than the steam-pressure on the inlet side of the valve 3, the valve 3 is opened again and steam passes through to again operate the 70 pump. Then, as soon as the air-pressure is raised again to exceed the steam-pressure, the valve 3 is closed, as already stated.

75 The valve 8 is not absolutely essential to the operation of the device. Its office is simply to relieve the valve 6 of the greater portion of the steam-pressure, and this it does by remaining on its seat while the valve 3 is open, it only allowing the pressure that can be produced through the port 9, which is 80 slight in comparison with that to which the whole area of the valve 8 is subjected.

85 20 represents a valve by which the air-pressure may be cut off, while the operation of the valves 3, 6, and 8 will not be interfered with, so that the air can be entirely closed off without interfering with the operation of the pump.

90 21 represents a screw located in the top of the cut-off, and which may be turned down against the wings 22 of the valve 3, if desired, to open the latter, in case it should stick. The screw 21 is preferably provided with a jam-nut 23, which may be screwed down tight upon the housing 5, to form a tight joint when the screw 21 is raised.

95 I claim as my invention—

1. In a governor for air-compressors, the combination of the valves 3 and 8, connected together, and piston 10, arranged to raise said valves, the valve 8 having a port 9 for the escape of steam, substantially as and for the purpose set forth.

2. In a governor for air-compressors, the combination of the valves 3, 8, and 6, piston 10, and valve 13, the valve 8 having a port 9, and the valve 6 having passage-ways between it and the housing, substantially as and for the purpose set forth.
3. In a governor for air-compressors, the combination, with the housing having a piston therein and the exhaust-port and ports 1 and 10, of two valves 3 6, opening in opposite directions, located in said housing between the exhaust-port and port 1, and adapted to be operated by said piston, and a connection between said valves, substantially as set forth.
4. In a governor for air-compressors, the combination, with the housing having the ports 1 and 2 and exhaust-port, and the piston 10, having neck 11, of two valves 3 6, opening in opposite directions, located in said housing between the port 1 and exhaust-port, and a valve 8, located between the valves 3 and 6, and having the port 9 and being secured to the valve 3, substantially as set forth.

FRANK LANSBERG.
